PISTON

Edward M. Svee, North Chicago, Ill.

Application April 21, 1944, Serial No. 532,079

2 Claims. (Cl. 123—78)

The invention relates to an engine, and more especially to a piston assembly for an internal combustion engine, suction pump, compressor or the like.

The primary object of the invention is the provision of an assembly of this character, wherein an added amount of displacement will be had within a cylinder having interfitting large and small pistons reciprocatingly operating therein, thereby increasing the power of the unit, whether it be an internal combustion engine, suction pump, compressor or the like, with resultant maximum efficiency in the operation thereof.

Another object of the invention is the provision of an assembly of this character, wherein the interfitting pistons are actuated in a novel and unique manner, concurrently with each other, one of the pistons being a booster in the working of the power unit.

A further object of the invention is the provision of an assembly of this character, wherein increased power is assured and at the same time less fuel consumption maintained.

A still further object of the invention is the provision of an assembly of this character, which is simple in construction, thoroughly reliable and efficient in operation, strong, durable, it being noiseless in the working thereof, and inexpensive to manufacture and install.

With these and other objects in view, the invention consists in the features of construction, combination and arrangement of parts as will be hereinafter more fully described in detail, illustrated in the accompanying drawings, which show the preferred embodiment of the invention, and pointed out in the claims hereunto appended.

In the accompanying drawings:

Figure 1 is a vertical sectional view of a power unit showing the piston assembly constructed in accordance with the invention applied thereto.

Figure 2 is a view similar to Figure 1 looking at right angles thereto.

Figure 3 is a top plan view of the piston assembly.

Figure 4 is a bottom plan view of the piston head.

Figure 5 is a fragmentary sectional view taken on the line 5—5 of Figure 2 looking in the direction of the arrows.

Figure 6 is a sectional view taken on the line 6—6 of Figure 1 looking in the direction of the arrows.

Figure 7 is a view similar to Figure 3 showing a slight modification.

Similar reference characters indicate corre-

sponding parts throughout the several views in the drawings.

Referring to the drawings in detail, particularly Figures 1 to 6, inclusive, A designates generally the usual cylinder block or casing within which the piston reciprocates and which is provided with the head 10, the cooling of the said block or casing being effected in any selected manner, and the head 10 has fitted thereto a spark plug 11 for location at any point in the combustion chamber which is desired, according to the type of engine in which the piston assembly forming the present invention is employed.

The piston assembly constituting the present invention, comprises a master piston head 12 which reciprocates within the block or casing, and through the medium of a wrist pin 13 has connection with a connecting rod or pitman 14, the latter being connected at 15 to the crank 16 of a crankshaft 17, as is common or usual.

Built within the piston head 12 is a piston cylinder 18, it being aligned with the longitudinal extent of the block or casing A to one side of the longitudinal central axis of the said head 12, while reciprocatingly fitted in this cylinder 18 is a small piston head 19, auxiliary to the master piston head 12. A connecting rod or pitman 20 has wrist pin connection 21 with this piston head 19, and also eccentric pivotal connection at 22 with a gear 23, which has its center stud axle 24 fitted in the connecting rod or pitman 14 for the master piston head 12, the gear 23 being in mesh with a companion gear 25 which is formed in sections bolted or otherwise connected together at 26 about the crank 16 and splined or keyed thereto as at 27, so that on reciprocation of the piston head 19 the crank 16 will be turned by these gears 23 and 25 enmesh with each other.

It should be seen that by the use of the piston assembly as hereinbefore described in an internal combustion engine now used in automobiles, there is afforded an additional amount of piston displacement, and in this fashion increasing the power of the engine.

In Figure 7 of the drawings, there is shown a slight modification of the assembly, wherein the master piston head 28 having several small piston heads 29 interfitted therewith in cylinders built within the latter, and in this manner greater piston displacement may be had. In Figure 6, there is shown the manner in which the pistons are operated by providing a second rod or pitman 20' having the eccentric pivoted connection at 22' with the gear 23' which is mounted on

the axle 24 fitted in the connecting rod or pitman for the motor piston head 28. The operation of the pistons 29 within the piston 28 will be, as previously described.

The assembly constituting the present invention involves the use of a duplex piston arrangement, these being operated in the manner as before stated. In the case of a two-cycle engine, the efficiency and power thereof can be increased by the use of the duplex piston assembly, and where the latter is used to pump gases or liquids, it will pump more per revolution than the usual single type of piston, the duplex type being a booster piston for a power unit.

While the piston assembly has been shown in the accompanying drawings as applied to an internal combustion engine, it is to be understood that the invention is also applicable to other uses such as with a suction pump, a compressor, a two

cycle internal combustion engine or a four cycle engine or the like.

What is claimed is:

1. In an assembly of the kind described, a cylinder, a crank shaft, a composite piston made up of a plurality of pistons interfitting with each other and movable independently of one another, a pitman directly connecting one of the pistons with the crank of said shaft, a gear carried by said pitman, a gear fixed to the crank of said shaft and meshing with the gear on said pitman, and a connecting rod connected eccentrically with the first named gear and also connected with the other piston.

2. The invention as described in claim 1, wherein said composite piston comprises several oppositely positioned auxiliary pistons within a main piston.

EDWARD M. SVETE.
